UNITED STATES PATENT OFFICE.

RALPH M. GROVE, OF BROOKLYN, NEW YORK, ASSIGNOR TO MERGENTHALER LINOTYPE COMPANY, A CORPORATION OF NEW YORK.

MATRIX-DISTRIBUTING MECHANISM.

1,074,945.

Specification of Letters Patent.

Patented Oct. 7, 1913.

Application filed December 28, 1911. Serial No. 667,881.

To all whom it may concern:

Be it known that I, RALPH M. GROVE, a citizen of the United States, and a resident of the borough of Brooklyn, county of 5 Kings, and State of New York, have invented a new and useful Improvement in Matrix-Distributing Mechanisms, of which the following is a specification.

My invention has reference to matrix distributing mechanism of the well known Mergenthaler type, represented in Letters Patent of the United States No. 436,531, and relates to improved means for stopping the action of the parts in the event of a matrix 10 being lodged in an improper position in the distributor. This distributor consists of a horizontal bar having longitudinal teeth on the lower V-shaped edge, adapted to engage and sustain matrices having in their upper 15 ends a V-shaped notch with teeth to engage those of the distributor bar, along which the matrices are carried by means of three parallel screws; two of which engage the upper edges of the matrix, while the third engages one of the lower edges.

The teeth of the distributor bar are permuted or varied in arrangement at different points in its length, and the teeth of the matrices representing the different characters are varied in arrangement to correspond; so that each matrix suspended from the bar is carried along the same by the screws until it arrives over its appropriate channel in the underlying magazine, whereupon all of the teeth of the matrix are released by the bar, so that the matrix may descend by gravity past the screws, toward the magazine.

In practice it occasionally happens that a descending matrix will fall out of position and lodge in the upper end of one of the magazine channels, or in a channel leading to the magazine, while still in engagement with one of the carrier screws. In such case the screw, acting against the matrix, tends to crowd the same sidewise against the side of the channel, with the effect of bending the matrix and endangering the integrity of the mechanism.

50 The object of my invention is to provide for the immediate stoppage of the distributor screws in such event.

To this end, it consists in providing one of the wheels through which the distributor screws are driven with a spiral slot or

surface, and mounting it so that when the rotation of the screws is arrested by the action of the matrix the wheel may continue its motion independently for a slight distance, the oblique slot at such time causing 60 the wheel to move laterally and, through suitable connections, trip the driving clutch out of action.

The essence of the invention lies in the employment of a screw-driving member having a limited independent rotation, and in utilizing this rotation, through suitable mechanism, to effect the stoppage of the distributor.

In the drawings I have shown my improvement applied to a Mergenthaler distributing mechanism of the form now in commercial use. All parts of the machine not shown may be of any ordinary or suitable construction.

Referring to the drawings: Figure 1 is a perspective view of one end of the distributing mechanism with the parts in operative position. Fig. 2 is a rear elevation of the same. Figs. 3 and 4 are longitudinal sections on the lines 3-3 and 4-4 respectively. Fig. 5 is a cross section on the line 5-5, Fig. 2, looking toward the left. Fig. 6 is a cross section on the line 6-6, Fig. 2.

Referring to the drawings, A, A represent portions of the framework, B the horizontal distributor bar, C, C' and C'', the synchronously operated parallel screws which engage the edges of the matrices D, to carry them along the bar. The lower screw C'', is driven by means of a gear E, mounted on its end and free to turn thereon to a limited extent, the hub of this gear being provided with an oblique or diagonal slot e', through which the driving pin e'' is inserted into the screw, so that when the gear is turned on the screw it will be caused to shift laterally. The gear E receives motion from the gear F, which is in turn driven by the gear G, secured to a spindle H, Fig. 4, mounted to turn in bearings on the frame. On this spindle there is mounted loosely a constantly driven belt pulley I, which communicates motion to the spindle and the gear G, through friction clutch J, consisting of a sleeve splined to the spindle H that it may shift endwise thereon, and provided with the friction surface j' to bear against the side of the pulley I, toward which it is urged by a helical spring K. The clutch J is pro-

vided, as shown in Figs. 1, 2 and 3, with an annular flange having on one side the inclined or stepped surfaces j^2 . In the normal condition of the parts the clutch is in contact with the pulley as shown in Fig. 1, and the parts are all kept in motion. For the purpose of tripping the clutch out of action at the proper times I provide a rock shaft K' , mounted on the main frame and carrying 10 the arm k , with a stud at its end, so that when the shaft is rocked to throw this stud into the path of the inclined faces on the clutch, one of the faces will engage against the stud, and thus the clutch will be forced 15 back laterally, out of contact with the pulley, as shown in Figs. 2 and 4, so that the latter and all the feed screws will stop. A spiral spring M , is extended from an arm (shown in dotted lines) on the rock shaft to the 20 main frame, and tends to throw the arm k into operative position. It is held normally out of action, however, by the arm L , pivoted to the rock shaft, and abutting at one end 25 against the stop N , as shown in Fig. 1, the spiral spring n , connected to the arm and main frame, tending to hold the parts in this position. The opposite end of the arm L , provided with an antifriction pulley, lies 30 adjacent to the face of the laterally movable gear E , before referred to, and by its pressure tends to hold this gear to the left.

During the normal operation the parts occupy the relations shown in Fig. 1—with the pin e^2 at the rear end of the oblique slot. 35 If during the operation of the machine a falling matrix lodges in the mouth of a magazine channel, or against the thread of the lower screw C^2 , as shown in Fig. 2, it will resist the rotation of the screw, and the 40 gear E will turn forward around the latter. During this independent rotation of the gear the pin e^2 and slot e' will cause it to move laterally toward the right, and the gear, in turn, will act on the arm L , disengaging its 45 forward end from the stop N , and thereby leaving the rock shaft K' free to turn under the influence of the spring M ; whereupon the arm k will engage the clutch and throw the same out of action in the manner 50 already described, thus bringing the distributing mechanism to a stop until the offending matrix is removed and the arm k thrown out of engagement with the clutch by hand, the arm L engaging automatically 55 to hold it in this position.

While I prefer to employ the inclined slot and pin, and to use them in connection with the screw driving gear, it will be understood that any corresponding inclined surfaces 60 may be employed between the driving gear or other driving member, the only requirement being that the driving member shall be capable of turning independently of the screw against a yielding resistance, and that 65 this independent motion of the driving mem-

ber shall be caused to effect the stoppage of the parts.

It is to be understood that the clutch mechanism may be of any suitable character, and that any suitable devices may be used between the driving member and the clutch, to control the latter. 70

Having described my invention, what I claim is:

1. In a distributing mechanism, a feed screw fixed against end motion, a driving gear connected to the screw to turn and move laterally thereon to a limited extent, and a stop device actuated by the lateral motion of the gear. 75

2. The distributor screw, the driving gear mounted to move spirally in relation to the screw, a clutch controlling member actuated by the lateral movement of the gear, and a spring tending to resist the independent movement of the gear, whereby resistance to the rotation of the screw is caused to move the gear and trip the clutch. 85

3. The distributor screw and the laterally movable gear connected thereto by the slot and pin, in combination with the driving clutch and the clutch-releasing devices actuated by the side motion of the gear. 90

4. In a distributing mechanism, a feed screw and driving connections therefor, said connections including two connected gears one arranged to rotate and move laterally in relation to the other, and a spring tending to resist said relative lateral movement. 95

5. In combination, the screw, the gear thereon, the spiral connection between said parts, the driving clutch connected with the gear, the rock shaft having the arm to throw the clutch out of action, the latch to hold the rock shaft, and spring connections tending to hold the parts in normal operative positions. 105

6. In a distributing mechanism of the class described, a feed screw, driving connections therefor, including two rotary members, one arranged to rotate against a yielding resistance in relation to the other, and a driving clutch controlled by the independent relative rotation of said rotary members. 110

7. In a typographical machine, the combination of a plurality of synchronously operated rotary distributing devices, with means connected thereto to arrest their rotary movement when their rotary synchronism is interrupted. 120

8. In a typographical machine, the combination with two rotatable distributing members normally operating in unison and one capable of a slight independent rotation relatively to the other, and means to arrest the rotation of said members and controlled in their action by such independent rotation. 125

9. In a typographical machine, the combination of two rotatable distributing members, driving means therefor, and mechanism independent of the driving means whereby the retardation of the rotary action of one arrests the rotation of the other of said members.

10. In a typographical machine, the combination of a plurality of rotary distributing devices, means to operate them normally in synchronism but arranged to be shifted out of their normal relations, and means connected to the distributing devices to arrest their rotary movement when their rotary synchronism is interrupted.

11. In a typographical machine, the combination of a plurality of rotary distributing devices, means to operate them normally in synchronism but mounted to yield in the event of undue strain thereon, and means connected to the distributing devices to arrest their rotary movement when their rotary synchronism is interrupted.

12. In a typographical machine, the combination with distributing mechanism comprising a plurality of rotary members operating in definite relation to each other, of means for arresting their rotation when such rotary relation is disturbed.

13. In a typographical machine, the combination of a plurality of rotary distribut-

ing devices, with means associated therewith to arrest their rotary motion, said means being inactive in the normal operation of the distributing devices but adapted to be rendered active by the abnormal rotary operation of said devices.

14. In a distributing mechanism, the combination of a rotatable feed screw, a driving member therefor and movable independently thereof in a rotary direction, and a stop device actuated by the independent movement of said member.

15. In a distributing mechanism, the combination of a rotatable feed screw and driving means therefor, with devices whereby the said means are thrown out of action by the arrest of said screw.

16. In a distributing mechanism, the combination of a rotatable feed screw adapted to be prevented from rotation by engagement with an obstructing type or matrix, driving means for the screw, and connections whereby the arrest of said screw throws the driving means out of action.

In testimony whereof I hereunto set my hand this fifteenth day of December, 1911, in the presence of two attesting witnesses.

RALPH M. GROVE.
